TOOL

William S. Miles, Hastings on Hudson, and Paul A. Voigt, Bellerose Manor, N. Y., assignors to Johns-Manville Corporation, New York, N. Y., a corporation of New York

Application January 24, 1941, Serial No. 375,744

9 Claims. (Cl. 81—3)

Our present invention relates to improvements in wall construction methods, and more particularly, to improved means for applying securing devices to the projecting shanks of nails or other fasteners driven through facing and sheathing elements.

Referring to our formerly copending application, now Patent #2,293,743, issued August 25, 1942, we have described a method of erecting a wall or partition structure employing a sheathing material of low nail-holding properties, such as the conventional fibre board. Shingles or other fastening elements are laid over the sheathing and nailed thereto, and securing clips or nuts are applied by means of a suitable tool to the nail shanks projecting from the rear face of the sheathing to retain the nails against withdrawal.

A principal object of the instant invention is the provision of an improved tool for use in the above referred to method, and more specifically, the provision of a tool which may be easily and rapidly manipulated.

Another object of the invention is to provide a tool of the type referred to which exerts an increased gripping action on the nail shank as greater pressure is applied to the securing device or nut as the same is forced along the shank.

A further object of the invention is the provision of such tool in which the shank gripping means or claw element is removable to permit replacement from time to time.

Our invention will be more fully understood and further objects and advantages thereof will become apparent when reference is made to the more detailed description thereof which is to follow and to the accompanying drawings, in which:

Fig. 1 is a face elevational view, with parts broken away, of a portion of a wall during the construction of which the present invention is employed;

Fig. 2 is a perspective view of the rear of the wall shown in Fig. 1;

Fig. 3 is a view similar to Fig. 2, illustrating the use of a modified type of fastener;

Fig. 4 is a perspective detail view on an enlarged scale of the type of fastener used in the construction of Fig. 2;

Fig. 5 is a perspective detail view on an enlarged scale of the type of fastener used in the construction of Fig. 3;

Fig. 6 is a sectional view on an enlarged scale taken on the line 6—6 of Fig. 2, and illustrating one stage in the operation of the tool of the instant invention;

Fig. 7 is a view similar to Fig. 6, illustrating a further stage in the operation;

Fig. 8 is an enlarged sectional view taken on the line 8—8 of Fig. 2;

Fig. 9 is a perspective view of the tool of the instant invention;

Fig. 10 is a detail view on an enlarged scale of an element of the tool of Fig. 9;

Fig. 11 is an end elevational view of the element of Fig. 10; and

Fig. 12 is a sectional view similar to Fig. 8 but with parts broken away, illustrating the operation of the invention with the modified form of fastener element.

Referring now to the drawings, and particularly to Figs. 1, 2 and 3, there is shown a wall structure which, for the purposes of illustration, comprises an exterior vertical wall, but which, as will be understood, may equally well be a roof wall or an interior wall of any suitable type. The wall shown comprises shingles 10 laid over sheathing 12 secured to suitable studs 14 in any desired manner, for example, where steel studs are used, by the means shown in our copending application Ser. No. 372,434, filed December 31, 1940.

Sheathing 12 comprises a material such as fibre board, plaster board, or the like, which, though readily adapted to receive the shingle securing nails 15, does not have sufficient nail-holding properties to permanently retain them. Nails 15 are preferably of the barbed shank type now conventionally used for asbestos-cement shingles, but any suitable type of barbed fastener may be used, for example, threaded members such as bolts or screws, the threads constituting the barbs desired for a purpose later described.

To secure the nails against withdrawal, clips or nuts 16 are employed. The clips or nuts may take various forms, two exemplary alternative constructions being illustrated in Figs. 4 and 5. However, in each case the clips or nuts comprise a spring steel member including an outwardly bowed central section. In the form shown in Figs. 2 and 4, the central section 18 is provided with cuts 20 defining aperture 22 and substantially parallel-sided spring tongues 24. The width of the aperture between the ends of spring tongues 24 is somewhat less than the smaller diameter of the nails 15 beneath the barbs. In the modification of Figs. 3 and 5, cuts 26 define triangular spring tongues 28 and a central aperture 30, the latter of somewhat smaller diameter than the nail shank.

In the construction of the wall assembly, after the shingles have been secured by nails driven

through the sheathing, clips 16 are applied by placing the same over the projecting nail shanks and forcing them into compressive engagement with the rear of the sheathing by means of tool 32.

In accordance with the instant invention, tool 32 (see particularly Figs. 6-11, inclusive) comprises a forked jaw 34 including extending tines 36 adapted to press upon the fastener or nut 16. The tines are preferably shaped as illustrated to permit force to be applied on the nut adjacent the nail or shank while allowing sufficient clearance to prevent interference with operation of the tongues 24 or 28. In the preferred embodiment of the instant invention, tines 36 of jaw 34 constitute substantially right angle flanges of a slotted arm 38, preferably integrally connected to an operating handle 40. Handle 40 comprises an outer operating arm 41, inner operating arm 42, and a connecting loop spring 43 preferably formed integrally with the arms. The inner arm 42 includes a forked extension 44. As illustrated particularly in Fig. 9, the widths of extension 44 and arm 42 are substantially greater than that of slot 31 and are separated in part by notches 46 defining a connecting neck 48 dimensioned to move freely within slot 31 of arm 38. Projecting at substantially right angles to arm 42, and preferably struck from the material thereof, are spacing members 50 adapted to contact the rear of the sheathing as indicated particularly in Fig. 8 to locate the tool in proper operative position when the same is held in substantial parallelism to the sheathing. The free ends or feet of members 50 are suitably rearwardly curved as shown.

Forked extension 44 carries a removable claw member 52 (see particularly Figs. 9, 10 and 11) formed of spring steel and including flanges 54 shaped to define dovetail slots 56. Flanges 54, and hence the dovetail slots, preferably taper slightly from a lesser width at the end adjacent a recess 58 to a greater width at the other end. The tines of forked extension 44 are of complementary shape to the dovetail slots 56 (see Fig. 9) and are arranged to be received therein. As will be readily understood, when the spring metal claw member 52 is forced endwise upon the tines of extension 44, it will be securely but removably retained thereon by reason of the wedging action of the tapering dovetail slots on the complementary tapering tines. The central portion of the claw member includes the recess 58 defined by outwardly curved margins 60, including preferably sharpened edges (see Fig. 11). The shape of slot 58 is suitably that illustrated in Figs. 8, 9 and 10 to adapt the claw to become readily positioned on a nail shank.

In the operation of tool 32, after one of the nuts 16 of a suitable type, for example, as shown in Figs. 2 and 4-8, inclusive, has been applied over a projecting nail shank 15, the tool is positioned with the feet of spacing members 50 preferably resting against the sheathing, and is moved forwardly until tines 36 of jaw 34 overlie the nut 16 and the nail shank is in notch 58 with lips 60 in biting engagement with the shank and preferably beneath a barb thereof (see Figs. 6 and 8). Handle portion 40 is first grasped and swung downwardly on feet 50 as a fulcrum to tension the nail, and the arms 41 and 42 are then pressed toward each other against the resistance of loop spring 43, with the result that tines 36 are moved toward the sheathing and press the nut 16 into binding engagement therewith, with-

drawal of the nail being prevented by the gripping action of the claw 52 upon its shank (see Fig. 7). Suitably, the lips of the claw are engaged beneath a barb of the nail as previously pointed out, but in view of the outwardly curved springy margins of notch 58, slippage is prevented in any event, as the downward pull of the nail on the margins brings them closer together and increases their bite on the nail. Upon release of pressure upon handle member 40, loop spring 43 moves arms 41 and 42 apart and the jaw and claw toward each other, whereby claw member 52 is released from its gripping action on the nail shank. The tool is then removed. Nut member 16 is retained in its spring pressed engagement against the sheathing by spring tongues 24 engaged beneath the barb of the nail shank, or by a biting action with the nail shank if a smooth nail is used.

As previously mentioned, the tool may be employed with any suitable type of securing nut 16 which is adapted to be forced upon the nail shank and maintain a fixed position thereon. Thus, Fig. 12 illustrates the use of the tool in the application of a nut of the type of Fig. 5, the nut being shown as forced to its final position.

Having thus described our invention in rather full detail, it will be understood by those skilled in the art that these details need not be strictly adhered to, but that various changes and modifications will suggest themselves without departing from the scope of our invention as defined by the subjoined claims.

What we claim is:

35. A tool for moving a locking member on a projecting shank, said tool comprising a jaw to engage said locking member to move the locking member along said shank, a claw member having opposed biting edges to grip said shank to prevent withdrawal movement thereof, handle members affixed to said jaw and claw, respectively, means operatively connecting said handle members for movement of said jaw and claw away from each other when said handle members are moved toward each other, said means including a loop spring integrally connected to said handle members to move them apart upon release of pressure thereon.
50. A tool for moving a locking member on a projecting shank, said tool comprising a jaw to engage said locking member to move the same along the shank, a claw member overlying said jaw and having opposed biting edges to grip said shank to prevent withdrawal movement thereof, a handle element affixed to said claw, a second handle element connected to said jaw and lying at the opposite side of said jaw from said claw, and spring means connecting said handle elements.
55. A tool for moving a locking member on a projecting shank, said tool comprising a jaw to engage said locking member to move the same along the shank, a claw member overlying said jaw and having opposed biting edges to grip said shank to prevent withdrawal movement thereof, a handle element, an extension of said handle element carrying said claw, a passageway in said extension, a second handle element including an arm extending through said passageway and connected to said jaw, and spring means connecting said handle elements.
60. A tool for moving a locking member on a projecting shank, said tool comprising a jaw to engage said locking member to move the same along the shank, a claw member overlying said jaw and having opposed biting edges to grip said shank to prevent withdrawal movement thereof, a handle element, an extension of said handle element carrying said claw, a passageway in said extension, a second handle element including an arm extending through said passageway and connected to said jaw, and spring means connecting said handle elements.
65. A tool for moving a locking member on a projecting shank, said tool comprising a jaw to engage said locking member to move the same along the shank, a claw member having opposed biting edges to grip said shank to prevent withdrawal movement thereof, a handle element, an extension of said handle element carrying said claw, a passageway in said extension, a second handle element including an arm extending through said passageway and connected to said jaw, and spring means connecting said handle elements.
70. A tool for moving a locking member on a projecting shank, said tool comprising a jaw to engage said locking member to move the same along the shank, a claw member having opposed
75. A tool for moving a locking member on a projecting shank, said tool comprising a jaw to engage said locking member to move the same along the shank, a claw member having opposed

biting edges to grip said shank to prevent withdrawal movement thereof, a handle element, an extension of said handle element carrying said claw, opposed notches in said extension, a second handle element spaced from and extending in the same general direction as said first handle element, spring means connecting said handle elements at the outer ends thereof, and a forked arm extending from the inner end of said second handle element, the tines thereof passing through said notches and defining said jaw.

5. A tool for moving a locking member on a projecting shank, said tool comprising a forked jaw to engage said locking member to move the same along the shank, and means to grip said shank to prevent its withdrawal during movement of said locking member, said means comprising a forked member having tines of dovetail transverse cross-section and a replaceable claw of resilient metal, the claw having inner biting edges and outer channeled extensions defining dovetail slots receiving the tines of said forked member in frictional locking engagement, and means operatively connecting said jaw and forked member.

6. A tool for moving a locking member on a projecting shank, said tool comprising a jaw to engage said locking member to move the locking member along said shank, a claw member including biting edges to grip said shank to prevent withdrawal movement thereof, handle members affixed to said jaw and claw, respectively, means operatively associating said handle members for movement of said jaw and claw away from each other when said handle members are moved toward each other, said means including mechanism for moving said handle members apart upon removal of pressure thereon.

7. A tool for moving a locking member on a projecting shank, said tool comprising a jaw to engage said locking member to move the locking member along said shank, a claw member having biting edges to grip said shank to prevent withdrawal movement thereof, handle members affixed to said jaw and claw respectively, means operatively associating said handle members for

movement of said jaw and claw away from each other when said handle members are moved toward each other, said means including mechanism for moving said handle members apart upon removal of pressure thereon, and means projecting from the handle member carrying said claw to space said handle member from a wall or the like through which said projecting shank protrudes.

10. 8. A tool for moving a locking member on a projecting shank, said tool comprising a jaw to engage said locking member to move the locking member along the shank, means to grip said shank to prevent withdrawal movement thereof, handle members affixed to said jaw and means respectively, means operatively associating said handle members for movement of said jaw and first-mentioned means away from each other when said handle members are moved toward each other, said second-mentioned means including mechanism for moving said handle members apart upon removal of pressure thereon, said first-mentioned means comprising a forked member having tines of dovetail transverse cross-section and a replaceable claw of resilient metal having inner resilient marginal portions and outer channeled extensions defining dovetail slots with said tines received within said slots in frictional locking engagement.

15. 9. A tool for moving a locking member on a projecting shank, said tool comprising inner and outer operating arms, a forked jaw carried by one of said arms to engage said locking member on opposite sides of said shank, and means carried by the other of said arms to grip said shank to prevent its withdrawal during movement of said locking member on said shank, said means comprising a claw including resilient, shank engaging, inner, marginal portions extending outwardly at an angle from the plane of the claw toward the plane of said outer operating arm, and means operatively connecting said operating arms.
